ATTORNEYS

UNITED STATES PATENT OFFICE.

NICOL MACNICOL, OF KAMLOOPS, BRITISH COLUMBIA, CANADA.

MEMORANDUM-PAD HOLDER.

Application filed June 6, 1923. Serial No. 643,761.

To all whom it may concern:

Be it known that I, NICOL MACNICOL, a subject of the King of Great Britain, and a resident of the city of Kamloops, in the 5 Province of British Columbia, Canada, have invented certain new and useful Improvements in Memorandum-Pad Holders, of which the following is a specification.

My invention relates to improvements in 10 memorandum pad holders the objects of which are to provide a means whereby a calendar pad having a plurality of loose leaves may be conveniently supported upon a vertical surface, such as at the side of a 15 wall telephone, and in a manner permitting the use of opposite sides of each leaf thereof for entering notes, further objects are to provide means for holding used leaves flat against the surface of the pad and to 20 provide a convenient holder for a pencil.

The invention consists essentially of a vertical panel having removably fixed staples for holding a pad or the like, and a projecting ledge under which a leaf holder is 25 slidably supported, as will be more fully described in the following specification in which:—

Fig. 1 is a front view of my invention.

Fig. 2 is a side view.

30 Fig. 3 is a vertical section showing the manner in which the used leaves are held in upright position.

In the drawings like characters of reference indicate corresponding parts in each 35 figure.

The numeral 1 indicates a panel of wood or other suitable material which is apertured as at 2 for fastening with screws or otherwise to the wall, the numeral 3 indicates a pair of staples one leg of which is threaded as at 4, see Fig. 3, and is provided with a nut 5, by which the staple is secured to the panel 1. 6 indicates recesses in the panel 1 to receive the end of the opposite 45 leg of the staples 3.

The numeral 7 indicates generally a shelf projecting from the face of the panel 1, which is set at a suitable distance above the staples 3 to accommodate the used leaves of 50 the pad 12 therebetween, the upper face of the shelf being provided with grooves 8 to form a holder for a pencil. 9 is a downwardly projecting strip secured to the outer edge of the shelf 7 having an aperture 10 in

which is slidably fitted a leaf holding plug 55 11.

The numeral 12 indicates a pad or calendar, perforated as at 13 for engagement of the several leaves thereof by the staples 3. 14 indicates that portion of the pad which 60 has been used and has been turned upwards and its leaves held in inverted position.

Having thus described the several parts of my invention I will now briefly explain its use.

65 A pad perforated as required is suspended upon the lower legs of the staples 3 and the staples secured to the panel 1 by the nuts 5 of the thread 4, as the front face of each leaf of the pad is filled, it is lifted to the 70 opposite leg of the staple and its free end is held in inverted position by the leaf holding plug 11, thus leaving the reverse side of each leaf available for further notes.

75 It will thus be seen that I have invented a simple and cheap device by which full and effective use may be made of a calendar or loose leaf pad attached thereto, and which permits of the leaves of such pad being snugly held in inverted position against the 80 panel of the device and leaving at all times the obverse side of one and the reverse side of another leaf available for instant use.

85 What I claim as my invention is:

A combined memorandum pad and pencil support comprising a base plate, means for supporting the pad on the base plate in such manner that each leaf of the pad may be separately swung from a depending to a 90 reverse position, and means for retaining the leaves in the last mentioned position comprising a pencil supporting shelf projecting outwardly from the base plate at a suitable point above the depending leaves, a plate secured to and depending below the 95 outer edge of said shelf, said plate being formed with an opening aligned with a guide groove provided in the underside of the shelf, a plug arranged to slide in said groove and through said opening, and a knob at 100 the outer end of said plug.

Dated at Kamloops, British Columbia, this 1st day of May, 1923.

NICOL MACNICOL.
